UNITED STATES PATENT OFFICE.

ROBERT DEANE, OF BROOKLYN, NEW YORK.

HINGE-LOCK.

SPECIFICATION forming part of Letters Patent No. 485,613, dated November 8, 1892.

Application filed February 25, 1892. Serial No. 422,775. (No model.)

To all whom it may concern:

Be it known that I, ROBERT DEANE, a citizen of England, residing at Brooklyn, in the county of Kings and State of New York, have 5 invented certain new and useful Improvements in Shutter-Locks; and I do hereby declare the following to be a full, clear, and exact description of the invention, such as will enable others skilled in the art to which it applies 10 to make and use the same.

This invention relates to a hinge-lock for shutters, blinds, or doors, the object being to produce a device simple and cheap in construction which may be applied to hinges ordinarily used and will serve to lock the doors, blinds, or shutters to which it is applied in a 15 desired position of adjustment.

The invention comprises a tube provided with a central orifice adapted to slide over 20 the knuckles or joints of the hinge, the walls of the tube being provided with slots symmetrically placed with reference to the walls of the tube. It also comprises a tube of this character provided with a plurality of slots 25 symmetrically placed, one of which is adapted to embrace one member of the hinge and another the other member, whether it be a right or left hinge. It also comprises a tube provided with a series of slots, so as to secure 30 the hinge in various positions of angular adjustment.

The invention will be more clearly understood by reference to the accompanying drawings, in connection with the following description. 35

Figure 1 represents a shutter, to which my hinge-lock is applied. Fig. 2 represents a perspective view of one form of my hinge-lock, showing a long slot and four auxiliary 40 slots for locking a shutter at different positions of adjustment. Fig. 3 shows a form of my device in which only two auxiliary slots are used.

The lock comprises a tubular structure, 45 preferably made of hard metal—as iron, steel, brass, bronze, or nickel—from which it may be conveniently cast. It may be cylindrical or polygonal in cross-section. The central opening should be of a diameter to fit over the joint or knuckles of the hinge to which it 50 is to be applied. The device will be made of graded sizes to suit the different grades of

hinges in use. Parallel to the axis of the recess is a slot, as indicated at A, which slot is made of a greater length than the width of 55 the strap B of the hinge. It is also provided with one or more additional slots C, which may be shorter than the slot A, so that if the device is placed with the slot A over the strap B of a hinge and the shutter turned until a 60 shorter slot aligns with the hook D of the hinge the lock will drop into a position by which the strap and hook of the hinge will be embraced by the two slots, thus effectually locking the shutter against angular movement. 65 In Fig. 1 the lock is shown as applied to a shutter thrown fully open. By providing one or more additional slots the shutter can be locked at an intermediate angle. A flexible support—such as a chain or cord, as shown at E—is provided, by which the lock may be secured to the frame or wall adjacent to the hinge, so that it may always be ready for use. In the case of blinds or doors opening upon the inside of a room or building, the lock may be 70 slipped upon the hinge when the shutter, door, or blind is closed. In such a case the strap and hook of the hinge lie superposed and the slot is brought into alignment with them and the locking device dropped over the joint. 75 By providing the device with two or more auxiliary slots, in addition to the long slot, it is adapted to be used with either a right or left hand hinge, so that the same device may be used for any of the purposes hereinbefore 80 described.

I am aware that it has been proposed to lock a shutter-hinge by means of a flanged tube in which the flange is tangential to one side of the tube. In such a device a different design must be used with right and left hinges, requiring two different castings. With my device the same pattern will apply to either a right or left hand hinge, the arrangement of the slots described permitting such an application. 95

Having thus described my invention, what I claim as new, and desire to secure by Letters Patent, is—

1. A hinge-lock for shutters, blinds, or doors, 100 comprising a tube adapted to slide over the hinge-joint and provided with a series of longitudinal slots in its walls, one of said slots being symmetrically placed with reference to

the walls of the tube, the other slots being at different angles to permit the hinge to be locked at different angles of adjustment, and a flexible support for securing the tube near

5 the hinge.

2. A hinge-lock comprising a tube adapted to slide over the hinge-joint and provided with a long slot to embrace both the strap and the hook and symmetrically-placed shorter slots

to admit of the use of the device on either right or left hinges.

In testimony whereof I affix my signature in presence of two witnesses.

ROBERT DEANE.
